(57) **CLAIM**

We claim the ornamental design for a tire paddle, as shown and described.

DESCRIPTION

This application is related to co-pending U.S. Utility application Ser. No. 17/891,081, filed Aug. 18, 2022.

FIG. 1 is a top and left perspective view of an tire paddle showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a top and right perspective of a tire paddle with environment.

The even-length broken lines in the figures represent portions of the tire paddle and environment that form no part of the claimed design.
